by Emery, Bott, Janney Harvey - Atlys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MASSACHUSETTS.

FASTENER.

Application filed February 1, 1923. Serial No. 616,292.

To all whom it may concern:

Be it known that I, FRED S. CARR, a citizen of the United States, and a resident of Newton, in the county of Middlesex, State of Massachusetts, have invented an Improvement in Fasteners, of which the following description, in connection with the accompanying drawings, is a specification, like characters on the drawings representing like parts.

This invention pertains to improvements in fasteners, and more particularly, though not exclusively, to improvements in fasteners primarily intended for securing carpets and the like. It is among the objects of the invention to present a superior fastener.

In the drawings, which show a preferred form of one embodiment of my invention, and a modification thereof:

20 Figure 1 is a plan view of a carpet with the fastener attached thereto;

Fig. 2 is a plan view on an enlarged scale of the carpet with the pile removed to show the engagement of the socket-holding prongs 25 with the warp of the carpet;

Fig. 3 is a section on the line 3—3 of Fig. 1, being partly in elevation;

Fig. 4 is a plan view of the socket prior to attachment thereof to the carpet;

30 Fig. 5 is a section on the line 5—5 of Fig. 3, being partly in elevation; and

Fig. 6 is a vertical section through a modification of my invention, being partly in elevation.

35 Referring to the drawings and to the preferred forms of my invention selected for illustrative purposes, I have shown a stud including a head 7, neck 8 and base portion 9 secured to a screw 10 entered in

40 a suitable stud-supporting part 11, such for instance as the floor of an automobile. The preferred form of socket illustrated includes a casing 13 containing a spring 14, which may be held in place by a top plate 15 through which pass socket-securing prongs 16, herein shown as six in number, and top plate securing prongs 17, herein shown as two in number. The socket-securing prongs 16 are passed through the warp of the carpet 18 while straight, and are then deflected outwardly, preferably by the suitably formed die of a press, so that they overlie portions of the warp of the carpet, preferably having their ends curved down-

wardly through the warp. This prong construction is peculiarly advantageous because, when an edge of the carpet is pulled upwardly to release the fastener, the pull of the carpet is into the curve of the prong instead of out of it, as is the case when the prongs are deflected inwardly to engage the warp of the carpet above the socket proper. The outward curving of the prongs is also advantageous in that for a given size of socket casing a wider area of carpet warp is 55 embraced within the prongs. Where the carpet has a pile, as is usually the case, the prongs are substantially if not entirely hidden by the pile. The preferred form of spring 14 herein illustrated is stamped 60 from a single sheet of metal to provide a stud-receiving aperture 20, a continuous rim 21, slots 22, 22 between the stud-receiving aperture and rim and communicating slots 23, 23 between the stud-receiving aperture and the first named slots 22, 22. The peripheral rim of the socket casing is spaced 65 from the socket opposite the connecting portions 24, 24 between the rim 21 of the spring and what may be termed the jaws 25, 25 70 so that, as the stud head 7 is entered in the stud-receiving aperture, the spring may elongate in a direction toward the connecting portions 24, 24, while the rim may become narrower at the dimension thereof opposite the connecting slots 23, 23. 75

In the preferred form of my invention illustrated in Fig. 3, the stud base 9 is of substantially the same diameter as the socket casing so that when the carpet above 80 the socket is stepped on, there will be no tendency to distort the casing and bind the spring 14.

In the modification of my invention illustrated in Fig. 6, the stud base 9' is of substantially smaller diameter than the socket casing 13', so that the top of the stud base may pass into the stud-receiving aperture, making the aggregate thickness of the fastener from floor to carpet somewhat less in 90 the embodiment of my invention shown in Fig. 3. Where this construction is used, I preferably throw down a rim 30 from the socket casing to contact with the floor 11' so that, when the socket is stepped on, no 100 harmful pressure is exerted on the spring. The prongs 16' of the modification of my invention preferably spread outwardly as 105

illustrated in Fig. 3, when engaged with the carpet.

While I have shown and described preferred forms of one embodiment of my invention, it will be understood that changes involving omission, substitution, alteration and reversal of parts, and even changes in the mode of operation, may be made without departing from the scope of my invention, which is best defined in the following claims.

Claims:

1. A fastener comprising, in combination, a stud having a head, a neck and a base, a casing presenting a stud-receiving aperture of sufficient diameter to admit said base, said casing presenting outwardly thrown portions to engage the floor when said stud is entered in said socket and thereby to relieve the spring in said socket of pressure when the carpet above said casing is subjected to pressure.
2. A carpet fastener socket comprising a two-part casing presenting a housing for a stud-engaging spring, one part of said casing presenting integral, outthrown, carpet-

engaging prongs passing through openings in the other part.

3. A carpet fastener socket comprising a base having a stud-receiving opening and an upstanding cylindrical wall, a plurality of carpet engaging prongs on said cylindrical wall, a stud-engaging spring in said base and a cover plate for said spring secured to said cylindrical wall, said prongs extending above said cover plate and adapted to be bent outwardly over the carpet web.

4. A carpet fastener socket comprising a base having a stud receiving opening and an upstanding wall, a plurality of carpet engaging prongs on said wall, a stud-engaging spring in said base and a cover plate for said spring secured to said wall, said cover plate presenting openings to receive said prongs, and said prongs being arranged to be bent outwardly and downwardly over the carpet web.

In testimony whereof, I have signed my name to this specification.

FRED S. CARR.
